UNITED STATES PATENT OFFICE.

JOHN W. VAN DYKE, OF PHILADELPHIA, PENNSYLVANIA.

RAILWAY TANK-CAR.

1,148,730.

Specification of Letters Patent. Patented Aug. 3, 1915.

Application filed November 28, 1908. Serial No. 464,947.

To all whom it may concern:

Be it known that I, JOHN W. VAN DYKE, a citizen of the United States, residing at Philadelphia, in the county of Philadelphia and State of Pennsylvania, have invented 5 certain new and useful Improvements in Railway Tank-Cars, of which the following is a specification.

This invention relates to the provision of 10 heating apparatus in the tanks of cars for transporting liquids on railways, more especially such liquids as lubricating oils, fuel oils and other heavy petroleum products which will not flow readily, if at all, at ordinary atmospheric temperatures. Heretofore the tank cars in which such liquids have been shipped have been provided 15 with steam heaters in order that the contents of the tanks may be heated and so made more fluid, when they are to be drawn off by the usual draw-off pipes at the bottoms of the tanks; but, so far as I am aware, every provision heretofore made for heating the contents of railway tank cars has been 20 open to objection on account of the liability of the steam pipes composing the heaters to leak at the joints or to be loosened from their fastenings to the walls of the tanks. These objections are largely at least over- 25 come by the aid of the present invention: in accordance with which in its best and most complete form a number of steam pipes are connected each at one end with a header and left sufficiently free otherwise for them to 30 expand and contract longitudinally with changes of temperature: while the header is secured to the tank bottom by a flanged base, which may be as large as necessary for a 35 permanent fastening (or as may be desired) 40 and in which are best formed the passages (one or more) for the inflow of the steam and the outflow of the water of condensation. The flanged base is also best formed with a reduced portion between the flange 45 and the body of the header; and the header is best divided into two chambers, one for steam and the other for the water of condensation, the former being connected by smaller inside pipes with the outer ends of 50 the inclosing pipes, whose inner ends are in direct communication with the latter chamber; but modification in these and in other respects can be made so long as the substance 55 is taken of any one or more of the claims at the end of this specification.

The invention also consists in part in cer-

tain particulars of construction hereinafter set forth.

In the accompanying drawings: Figure 1 is a view in vertical longitudinal and nearly 60 central section of the tank of a railway tank car, provided with heating apparatus in accordance with the invention in its best and most complete form; Figs. 2 and 3 are cross sections of the same on lines A A and B B 65 respectively of Fig. 1, looking in the direction of the arrows; Fig. 4 is on a larger scale and is a plan view of the header, broken away near one end to show a portion in horizontal section; and Fig. 5 is a vertical section on line C C of Figs. 1 and 4. Fig. 6 is a detail view in section on line D—D of Fig. 4.

Within the tank *a*, which is, as shown, of the customary cylindrical form and is to be 75 mounted in a horizontal position in any known or suitable way on wheeled trucks and provided with draft rigging (not shown) for movement on the rails of a railway, there are a number of pipes *b* connected each at one end with a header *c*; which, as shown, lies crosswise of the tank, the pipes *b* running longitudinally of the same. At their outer ends the pipes *b* are 80 closed, best by welding so as to avoid joints: 85 and they are left sufficiently free to expand and contract longitudinally. They are held from longitudinal movement bodily by their connection with the header *c*; which is fastened to the tank bottom; and transverse motion of them is prevented by attachment to cross-bars *d*, also secured to the tank bottom. Each pipe is held by a loop *e* whose ends are fastened to the corresponding cross-bar 90 (Fig. 3).

The header *c* has a flanged base, which at *f*, intermediate the flange *g* and the body of the header, is, as compared with the latter, of reduced area in horizontal section. This construction is advantageous, in that it interposes less obstruction to the flow of the liquid contents of the tank to the draw-off pipe *h* than a flanged base of larger dimensions would do, and also it is believed to lessen the stresses due to the alternate heatings and coolings which result when steam is applied and cut off. Passages *j* for the inflow of steam and *k* for the outflow of water are formed in this base, within the circle of rivets *l* by which the header *c* is 100 fastened to the tank bottom. There is, therefore, no danger of letting water into the oil 105 110 115

in the tank by leakage at those places where the connection is made between the heater inside and the conveyer of steam and water of condensation outside the tank *a*. The 5 broad flange *g* gives a support able to resist the shocks to which the car is exposed in running and in coupling. A tight joint around the edge of the flange is made by calking. As shown, the arms of the header 10 *c* project from the base *f* on opposite sides of the latter.

The header is shown as divided into two chambers by means of the partition *m* parallel with the flange *g* of the base *f* and transverse to the passages *j* *h* in said base. This 15 partition *m* forms the floor of one chamber and a part of the roof of the other chamber. The passage *h* communicates by means of the latter chamber with the pipes *b* on opposite 20 sides of the header. As shown in Fig. 5, the horizontal partition *m* slopes downward toward the passage *j*; so that any condensation in the overlying chamber will flow toward said passage *j*; which opens 25 into said overlying chamber. The chambers are each provided with threaded openings; which openings are of different diameters and are placed a small hole *r* behind each larger ones, but eccentric with reference 30 thereto. As shown, the front and rear walls of the upper chamber (see Fig. 4) opposite the openings *s* are curved inward, so that spaces are there shown (see also Figs. 1 and 6) between the walls in which the openings 35 *r* are formed and those in which the openings *s* are located, such spaces constituting in effect extensions upward of the lower chamber. The larger holes receive the ends 40 of pipes *b*, which are screwed fast therein, best inclined so as to drain toward the header. The smaller holes receive the ends 45 of pipes *n*, which are inclosed within pipes *b* and are open at their outer ends within the latter and which are best inclined to drain away from the header.

At *p* is shown a nipple for attachment of a pipe (not shown and not ordinarily a part of the car) for connection with a source of steam for heating. At *q* is shown a drain 50 pipe for the water of condensation.

In use the tank *a* is filled with the liquid to be transported. As this would be in a fluid condition, the pipes *b* can be left empty and unconnected with a source of 55 steam. In transportation it would not be necessary to keep the liquid fluid. But, of course, connection with a source of steam could be made at either or both of these times, if desired. When it is desired to 60 empty the tank of its contents, the nipple *p* is connected with a steam supply pipe. The steam flows through passage *j* into the upper chamber and is delivered by the small pipes *n* into the far ends of the pipes *b*. In 65 these the steam condenses in imparting heat

to the contents of tank *a* by conduction through the walls of pipes *b*; and the water of condensation flows back to the header *c* and is discharged by pipe *q*; with which latter a pipe leading to any desired place 70 may be connected. On account of the inclination of the pipes *b* and *n*, and the connection of the passages *j* and *h* with the bottoms of their corresponding chambers, no water need stand in the heating apparatus to be a source of danger by freezing 75 therein.

I claim as my invention or discovery:

1. The tank of a railway tank car, having therein a header which is provided with means for establishing an outside pipe connection in order to introduce fluid into the interior of said header and has a drainage 80 passage for the discharge of liquid from the header and which is mounted on and upheld by a single support in the form of a flanged base secured by its flange to the tank, and also having therein a number of pipes which are connected with said header at one end and are closed and left free at the other end 85 so as to expand and contract longitudinally, substantially as described.

2. The tank of a railway tank car, having therein a header which is provided with an attaching flange and is secured by its flange 90 to the tank bottom, and also having therein a number of pipes which are free to expand and contract longitudinally and are connected with said header, the tank bottom being 95 perforated under said header for allowing an outside pipe connection to be made directly with said header, and the header being provided with means for establishing an outside pipe connection directly with said header, substantially as described.

3. The tank of a railway tank car, having therein a header which is mounted on and upheld by a single support in the form of a flanged base secured by its flange to the tank bottom, and also having therein a number of pipes which are free to expand and contract longitudinally and are connected with said header, the tank bottom being 100 perforated under said header for allowing an outside pipe connection to be made directly with said header, and the header being provided with means for establishing an outside pipe connection directly with said header, substantially as described.

4. The tank of a railway tank car, having 105 therein a header, which is provided with means for establishing an outside pipe connection in order to introduce fluid into the interior of said header and has a drainage 110 passage for the discharge of liquid from the header and which is mounted on and upheld by a single support in the form of a flanged base and which comprises hollow arms projecting from opposite sides of said base and is secured by the flange of said base to the 115

5 tank bottom with said arms extending crosswise of the tank, and also having therein a number of longitudinally disposed pipes which are connected at one end with the 5 arms of said header and are closed and left free at the other end so as to expand and contract longitudinally, substantially as described.

10 5. The tank of a railway tank car, having therein a header which is provided with a flanged base and is secured to the tank bottom by the flange of said base and which is divided into chambers by a partition parallel with the flange of said base and is formed 15 with two sets of openings of different diameter, and also having therein two sets of horizontal pipes of different diameter which are free to expand and contract longitudinally and are disposed in horizontal rows 20 and are connected with said header, the openings of smaller diameter receiving the pipes of smaller diameter and being arranged each of them behind an opening of larger diameter, the openings of larger diameter receiving the pipes of larger diameter, and the pipes of larger diameter inclosing those of smaller diameter, substantially as described.

25 6. The tank of a railway tank car, having therein a header which is provided with a flanged base and is secured to the tank bottom by the flange of said base and which is divided into chambers by a partition parallel with the flange of said base and is formed 30 with two sets of openings of different diameter, and also having therein two sets of horizontal pipes of different diameter which are free to expand and contract longitudinally and are disposed in horizontal rows and are 35 connected with said header, the openings of smaller diameter receiving the pipes of smaller diameter and being arranged each of them behind an opening of larger diameter, with its center above the center of the latter, the openings of larger diameter receiving the pipes of larger diameter, and the pipes of larger diameter inclosing those of smaller diameter, substantially as described.

40 7. The tank of a railway tank car, having therein two sets of pipes of different diameter, and a header with which said pipes are connected, said header having a flanged base and hollow arms projecting from said base 45 on opposite sides of the latter and being di-

vided into chambers by a partition parallel with the flange of said base and formed with two sets of openings of different diameter for receiving the ends of the two sets of pipes respectively, and each of the smaller 60 openings being placed eccentrically behind one of the larger openings, substantially as described.

8. The tank of a railway tank car, having therein pipes and a header with which said 65 pipes are connected, said header having a flanged base and hollow arms projecting from said base on opposite sides of the latter and being divided into chambers by a partition parallel with the flange of said 70 base and being formed with two sets of openings for receiving the ends of the pipes, and each of said chambers being provided with one set of said openings, substantially as described. 75

9. The tank of a railway tank car, having therein a header with flanged base secured by its base flange to the tank bottom and also having therein a number of pipes which are connected with said header and 80 are free to expand and contract longitudinally, the tank bottom being perforated under said header and the latter having passages which terminate at different levels inside of the header and open into the space 85 outside the tank through that part of the tank bottom which underlies said header, substantially as described.

10. The tank of a railway tank car, having therein a header with a flanged base and 90 hollow arms secured by its base flange to the tank bottom in such manner that the said arms extend crosswise of the tank, and also having therein a number of pipes which are disposed lengthwise of said tank and are 95 connected with said header arms and are free to expand and contract longitudinally, the tank bottom being perforated under said header and the latter having passages which terminate at different levels inside of the 100 header and open into the space outside the tank through that part of the tank bottom which underlies said header, substantially as described.

In testimony whereof I have affixed my 105 signature in presence of two witnesses.
